UNITED STATES PATENT OFFICE.

WALTER V. TURNER, OF WILKINSBURG, PENNSYLVANIA, ASSIGNOR TO THE WESTINGHOUSE AIR BRAKE COMPANY, OF PITTSBURGH, PENNSYLVANIA, A CORPORATION OF PENNSYLVANIA.

FLUID-PRESSURE BRAKE.

1,129,318.

Specification of Letters Patent.

Patented Feb. 23, 1915.

Application filed March 27, 1906. Serial No. 308,310.

To all whom it may concern:

Be it known that I, WALTER V. TURNER, a citizen of the United States, residing in Wilkinsburg, in the county of Allegheny and State of Pennsylvania, have invented 5 certain new and useful Improvements in Fluid-Pressure Brakes, of which the following is a specification.

This invention relates to automatic air 10 brake systems for railway trains, and more particularly to the locomotive or engine brake equipment for such systems, one of the main objects being to provide an apparatus of this type, in which a single engineer's 15 brake valve may be employed for controlling the automatic brakes of the engine and train, either conjointly or controlling the engine brakes independently of the train brakes, whereby the train brakes may be released and recharged while holding the engine 20 brakes applied, or the engine brakes may be released and applied as desired without affecting the train brakes, and regardless of the position of the latter, that is, as to 25 whether said train brakes are released or applied, the brake valve being provided with suitable ports and a sufficient number of 30 positions to produce these results.

In my prior application, Serial No. 244,265, filed Feb. 6, 1905, is disclosed an apparatus somewhat similar to my present improvement and having a single engineer's 35 brake valve with suitable ports and positions whereby the engine brakes may be applied and released independently of the train brakes provided the latter are off, but not if said train brakes are applied.

In order to be able to apply and release the engine brakes independently of the train 40 brakes, both when said train brakes are released and also when applied, it is important that the feed supply to the train brake pipe should be maintained when the train brakes are off and the engine brakes are being 45 operated independently, and it is also necessary to prevent feeding the train brake pipe to raise the pressure therein while the train 50 brakes are on and the engine brakes are being operated independently, as that would effect a release of the train brakes. An apparatus having all of these desirable functions and advantageous features is covered by my prior pending application, Serial No. 287,527, filed Nov. 15, 1905, in which two 55 independently operable brake valves are em-

ployed, the engineer's brake valve for controlling the automatic engine and train brake system, and an independent or "straight air" brake valve for controlling the engine brakes independently. In that 60 construction the feed to the train brake pipe is controlled by the engineer's brake valve, so that this supply is maintained when this valve is in running position with the train 65 brakes released and the engine brakes are being operated by the independent brake valve; also, if the engineer's brake valve is in lap position with the train brakes applied, the train brake pipe pressure is not affected by the independent operation of the 70 engine brakes with the separate valve. When these functions are combined into a single brake valve or a valve mechanism 75 operated by a single handle, as in my present invention, it is necessary in the so-called 80 "straight air" positions, or those positions of the valve controlling the engine brake independently, to maintain the train brake pipe pressure in order to prevent the same from being reduced on account of leakage. 80

According to my present improvement, I 85 employ a maintaining feed valve device, so controlled by the engineer's brake valve, that in the "straight air" positions it operates to automatically maintain the train 90 brake pipe pressure at whatever degree obtained in said pipe at the time the engineer's 95 brake valve is turned to the said independent positions for operating the engine brakes. Thus, if the train brakes are off, and the 100 automatic system fully charged, when the engine brakes are operated independently the train pipe pressure will be maintained charged at the normal degree of pressure, while, if the train brakes have been previously applied and are on at this time of 105 independent operation of the engine brakes, the train pipe pressure will be maintained at whatever degree of reduction was made when said automatic train brakes were applied. In this way, the same positions may be used at all times for operating the engine 110 brakes independently, regardless of whether the train brakes are on or off. Any suitable means may be employed for maintaining the train pipe pressure in the "straight air" positions of the engineer's brake valve when the train brakes are off, and for preventing a feeding up of the train pipe pressure in these positions when the train brakes are 110

applied. For this purpose I prefer to employ a maintaining feed valve device, such as is covered in Patent No. 857,912 of myself and F. L. Clark, dated June 25, 1907, the same being connected up to the engineer's brake valve according to my present improvements to give the desired results.

In said prior patent the maintaining feed valve device is so connected to the engineer's brake valve as to operate automatically to maintain the train pipe pressure constant at any given degree of reduction when the engineer's brake valve is in lap position, while according to my present improvement it not only maintains the train pipe pressure constant in the lap position but also in the "straight air" positions during the independent operation of the engine brakes.

20 Another feature of my present improvement relates to the control of the feed valve device in the full release position of the engineer's brake valve, whereby an excess pressure from the main reservoir may be admitted to the train pipe without a separate port for that purpose, and comprises a port or other means controlled by the engineer's brake valve in full release position for causing the feed valve to stand wide open regardless of the degree of pressure in the train pipe and thereby supply excess pressure from the main reservoir through the feed valve and the supply port in the engineer's brake valve as long as the same 25 remains in full release position, but when turned to running position the train pipe pressure regulates the supply of fluid through the supply port of the engineer's 30 brake valve to the train pipe and limits the pressure to the desired maximum degree.

Another feature of my present invention relates to the so-called distributing valve device which controls the supply of air to the engine brake cylinders when operating either with the automatic system or with the direct independent system, as set forth in my two prior applications, above referred to, one object being to secure a more sensitive operation of the valve mechanism subject to variations in train pipe pressure by the use of a small graduating valve having an independent movement with the piston relative to the main valve; and another object being to provide a higher degree of pressure in the engine brake cylinders than in the application chamber of the distributing valve device, by the use of a differential piston for actuating the brace cylinder supply valve.

60 In the accompanying drawings, Figure 1 is a diagrammatic view showing in elevation a fluid pressure brake system embodying my improvements; Fig. 2 a similar diagrammatic view, on a larger scale, showing the engineer's brake valve seat in plan, and

the maintaining feed valve and the distributing valve devices in vertical section; Fig. 3 a vertical section through a portion of the engineer's brake valve showing the rotary valve and equalizing piston; Fig. 4 a face view of the rotary valve of the engineer's brake valve; Fig. 5 a vertical section of the rotary valve on a larger scale, taken on the line X—X of Fig. 4; and Figs. 6 to 14, inclusive, diagrams illustrating the various 70 positions of the rotary valve of the engineer's brake valve, the ports in the valve seat being indicated by the shaded portions, those in the face of the rotary valve by heavy lines, and the cavities in said valve 75 by dotted lines.

According to the construction shown in the drawings, the brake equipment comprises a main reservoir 15, connected by pipe 16 with the distributing valve device 19 and to the main valve 25 of the feed valve device, from which a pipe 24 leads to the port 38 and the rotary valve chamber of the engineer's brake valve 17, which is provided with the usual equalizing piston 49 and chamber 48 communicating through passage 23 with equalizing reservoir 22, and is connected to the train brake pipe 18, which leads to the distributing valve device 19, and also extends through the train to the car brake equipments comprising the usual triple valve 35, auxiliary reservoir 36, and brake cylinder 37.

The feed valve mechanism is preferably of the maintaining type, similar to that disclosed in the Turner and Clark Patent No. 857,912, before referred to, and comprises a main valve with a regulating device 26 and a maintaining device 27 for controlling the action of said main valve.

Referring to Fig. 2, the valve casing 25 contains valve chamber 88 and piston chamber 92, with main valve 89 and piston 90 for controlling the feed port 91, communicating with pipe 24 and the rotary valve 110 chamber of the engineer's brake valve. This space also communicates through passage 104 with dia; bram chamber 94 having dia- phragm 95 and adjustable spring 97 for operating the regulating valve 96. The feed passage also communicates with the chamber 99 on one side of the diaphragm 100, which is subject on its opposite side to the pressure of the maintaining chamber 98 and operates the small regulating valve 101, 115 which at certain times controls the release of fluid from the piston chamber 92 through the passage 105. A small reservoir 31 may be connected with the maintaining chamber 120 to give the desired volume thereto.

For coöoperating with the feed valve mechanism and distributing valve device the seat of the engineer's brake valve may be provided with the following ports, train pipe port 39 leading to the train pipe 18, ports 125

41 and 44 communicating with the equalizing reservoir chamber, port 42 communicating with pipe 30 leading to the maintaining chamber 98 of the feed valve mechanism, port 43 leading to the train pipe passage, port 46 communicating with pipe 29 leading to piston chamber 92, port 47 communicating with pipe 28 leading to the regulating valve 96 of the feed valve mechanism, port 45 communicating by pipe 32 with the application chamber of the distributing valve device, and exhaust port 40 leading to the atmosphere.

In the rotary valve 50 is formed a main cavity 51 having port openings 53, 54, 58, 59, 60, 62 and 63 in the face, while the valve is also provided with through ports 52, 55 and 57, and other small cavities 56, 61, and 64 in the face of the valve.

20 For the purpose of controlling the supply and release of fluid to and from the engine brake cylinders, a distributing valve device similar to that disclosed in my prior application above mentioned may be employed, 25 and this comprises a triple valve portion having a piston 67 operating in chamber 66 in response to variations in train pipe pressure to move a valve in chamber 68 to control the supply of fluid from the auxiliary 30 chamber 69 to the application chamber 70, and a brake cylinder supply and release valve mechanism composed of supply valve 81 in chamber 80, and release valve 85 in chamber 84, both operated by stem 83 of a 35 governing piston, which is subject to the pressure of the application chamber on one side and of the brake cylinder on the other, the valve chamber 84 communicating directly with pipe 21 leading to the brake 40 cylinders 20 of the engine or engine and tender.

According to one of the features of my present improvement, the governing piston is formed of differential heads 78 and 79, the 45 former being subject to the pressure of chamber 77, which communicates through port 71 with the application chamber 70 and forms a part thereof, and the latter being exposed on its opposite side to the brake 50 cylinder pressure in valve chamber 84, the space between said piston heads being open to the atmosphere, if desired. In this manner any desired ratio between the pressures 55 of the application chamber and the engine brake cylinders may be produced by forming the differential piston heads of suitable areas.

Another feature wherein the present structure is differentiated from that of the 60 former application, comprises the graduating valve 72 operated by the stem 71' of the triple piston 67 and having an independent movement relative to the main slide valve 73 for controlling the port 74 therein, whereby 65 the valve is rendered more sensitive in its

action. The main slide valve 73 is provided with a cavity 75 adapted to connect ports 71 and 76 when it is desired to release the application chamber by the action of the triple valve, as on the second engine in double-heading service, in which case the cock 33 may be turned to open port 76 to the atmosphere.

The operation of my improved apparatus is as follows:—With the engineer's brake valve in running position, as indicated in Fig. 7, compressed air from the main reservoir flows through pipe 16 to feed valve chamber 88, where it acts upon the piston 90 and opens the main feed port 91, thence flowing through pipe 24 and port 38 to engineer's brake valve chamber above the rotary valve. In this position the ports 46 and 47 are connected by cavity 64, so that communication is established from piston chamber 92 through pipes 29 and 28 to the regulating valve 96. As the pressure which then exists at the supply port 91 and in the regulating chamber 94 beneath the diaphragm 95 is less than the desired degree 90 of maximum train pipe pressure for which the spring 97 is adjusted, the valve 96 remains open, thereby releasing fluid, which leaks around the piston 90, to the atmosphere, so that the feed valve port 91 remains 95 open and air continues to flow through ports 52 and 39 of the engineer's brake valve to the train brake pipe 18, where it operates to charge the auxiliary reservoirs throughout 100 the train in the usual way. Air also flows through ports 55 and 41 to the equalizing reservoir and through ports 44, 43, cavity 56 and port 42 to pipe 30 and the maintaining chamber 98 and reservoir 31. Pressure also rises at the same rate in chamber 99 105 on the opposite side of maintaining diaphragm 100, being in communication with the feed pipe through port 104.

The auxiliary chamber 69 may be charged from the train pipe through a feed 110 groove around the triple piston 67. At the same time, the application chamber 70 is in communication through port 71, pipe 32, ports 45, 59, cavity 51 and ports 53 and 40 with the atmosphere, so that the engine 115 brake cylinders 20 are released through pipe 21, chamber 84, and exhaust port 86. When the pressure supplied through the feed valve rises to the desired maximum degree of train 120 pipe pressure for which the spring 97 is adjusted, the diaphragm 95 operates to close the regulating vent valve 96, whereupon the pressure from the main reservoir equalizes 125 around the piston 90 and the spring 93 moves the piston and slide valve 89 to close the feed port 91 and prevent further increase in the train pipe pressure.

To make an application of the brakes by the automatic system on both locomotive and train, the engineer's brake valve is 130

turned to service position, illustrated in Fig. 13, thereby permitting a preliminary discharge of air from the equalizing reservoir through ports 41, 60, cavity 51, and ports 53 and 40 to the exhaust. At the same time, it will be noticed that the maintaining reservoir is in communication with the equalizing reservoir through port 42, cavity 61 and port 41, so that precisely the same amount of reduction will be made in both reservoirs.

When the desired amount of reduction has been made and the brake valve is turned to lap position, Fig. 12, the preliminary discharge ports 41, 60 and 42 are closed, so that air at the desired degree of reduction is sealed up in the equalizing reservoir and in the maintaining reservoir. The equalizing piston 49 operates to open the train pipe discharge valve and reduce the train pipe pressure to the same degree in the usual manner.

In the service and lap positions of the brake valve, the ports 46 and 47 are closed, so that the position of the regulating valve 96 has no effect upon the feed valve piston which is now controlled by the regulating valve 101 operated by maintaining diaphragm 100.

As the port 52 of the rotary valve is open to the train pipe port 39 in the lap position, train pipe pressure exists in pipe 24 and through port 104 in chamber 99 above diaphragm 100, while the under side of said diaphragm is subject to the sealed pressure of the maintaining chamber.

The reduction in train pipe pressure operates to apply the automatic train brakes by the action of the triple valves in the usual way. On the engine, the reduction in train pipe pressure causes the piston 67 to move outward with the graduating valve 72, opening port 74 and then moving the main slide valve 73 to register port 74 with port 71. Air then flows from the pressure chamber 69 to the application chamber 70, charging the same to the desired degree, whereupon the pressure in the chamber 69 falls to an amount slightly less than the train pipe pressure, which then moves the piston and the graduating valve 72 sufficiently to close the port 74. The pressure in application chamber 70 and chamber 77 acting on piston head 78 and stem 83 moves the valve 85 to close exhaust port 86, and the valve 81 to open port 82 and supply air to the valve chamber 84 and through pipe 21 to the brake cylinders 20. As the brake cylinder pressure rises to a point such that the total pressure on piston 79 equals that acting on piston 78 the spring 87 actuates the stem 83 and valve 81 to close the supply port 82. By means of the differential pistons 78 and 79 a higher degree of pressure will be secured in the engine brake cylinders than is produced in the application chamber.

In order to effect a release of brakes on locomotive and train, the brake valve may be turned first to release position and then to running position. In release position, Fig. 6, air is supplied through ports 52 and 39 to the train pipe when the increase in pressure causes the usual action of the triple valves throughout the train to release the car brakes. This increase in train pipe pressure also moves the piston 67 with valves 72 and 73 to normal position and recharges the auxiliary pressure chamber 69, but the engine brake is still held applied, since the port 45 which communicates through pipe 32 and port 71 with the application chamber is still held closed at the brake valve in release position. The result of this is to cause a bunching of the train and prevent a surging ahead of the locomotive at the time of releasing brakes. This feature is also present in the apparatus disclosed in my prior applications above mentioned. When the engineer's brake valve is then turned to running position, the air from the application chamber is discharged to the atmosphere through 45, 59, 53 and 40, and the brake cylinder pressure acting on piston 79 moves the valve 85 to open exhaust port 86, thereby releasing the air from the brake cylinders of the engine, or both engine and tender, if desired, to the atmosphere.

When the brakes are applied and the engineer's brake valve is in lap position, with the port 52 open to train pipe port 39 and the feed valve controlled by the pressure sealed up in the maintaining chamber, as before described, it will be seen that, should there be any leakage from the train pipe tending to reduce the pressure therein, the maintaining diaphragm 100 will operate the regulating valve 101 to open the main feed valve sufficiently to supply all such leakage and maintain the train pipe pressure constant at the given degree of reduction, and to this extent the action of the present device is similar to that of prior application of Turner and Clark, above referred to. A light spring 102 may be employed, if desired, to bear upon the diaphragm 101 and assist the pressure of the maintaining chamber.

A novel and important feature of the present apparatus comprises means, such as a port 63 in the rotary valve, for opening communication from the feed valve piston chamber 92 through pipe 29, port 46 and outlet ports 53 and 40, in the release position of the engineer's brake valve, see Fig. 6, whereby the pressure is released from the back of piston 90 and the main reservoir pressure in valve chamber 88 holds the feed port 91 wide open and supplies air at the excess main reservoir pressure directly to the train pipe, as long as the engineer's brake valve remains in this position. By

this means the feed valve device may be located between the main reservoir and the engineer's brake valve, and the advantages of the excess main reservoir pressure may 5 be secured without an additional pipe connection from the main reservoir to the brake valve.

If, when the brakes are applied, both on the locomotive and throughout the train, it 10 is desired to release the train brakes only and recharge, while holding the engine brakes applied, the engineer's brake valve may be turned from lap to train release position, Fig. 8, in which the cavity 64 connects the ports 46 and 47, so that the feed valve is controlled by the diaphragm 15 and regulating valve 96, the same as in running position, and air flows from the feed valve through ports 52 and 39 to the 20 train pipe, releasing the triple valves on the cars and recharging the system up to the normal degree for which the spring 97 of the feed valve is adjusted. But, at the same time, the engine brakes are held 25 applied, since the port 45, which communicates with the application chamber of the distributing valve device is held closed at the engineer's brake valve. The engine brakes may then be released or graded 30 down, as desired, by turning the engineer's brake valve to running position, as before described.

If, when the automatic brake is applied on the locomotive and train, it be desired 35 to release the engine brakes independently and hold the train brakes applied, the brake valve may be turned from lap to the so-called straight air release position, Fig. 9, in which the port 45 registers with port 58 40 in the rotary valve and the air from the application chamber of the distributing valve device is released to the atmosphere through cavity 51 and ports 53 and 40, so that the engine brakes are immediately released 45 by the action of the piston 79 and exhaust valve 85, as before described. At the same time, the ports 46 and 47 are disconnected and closed, so that the regulating valve 96 is cut out and the feed valve is 50 then controlled by the maintaining dia- phragm 100, which is still subject to the pressure sealed up in the maintaining reservoir, since the port 42 communicating 55 therewith remains closed and operates to maintain the train pipe pressure at the given degree of reduction in the same manner as when the brake valve was in lap position, without affecting the train brakes. The latter are therefore held applied while 60 the engine brakes are released. If desired, the engine brakes may then be applied again independently without affecting the train brakes by turning the brake valve to straight air application position, Fig. 11, in which port 57 registers with port 45,

and air is charged directly from the brake valve chamber to the application chamber 70 of the distributing valve device, which then operates as before described to supply air to the engine brake cylinders. The 70 brake valve is then turned to straight air lap position, Fig. 10, in which the port 45 is closed and the engine brake held applied. In both of these last positions the port 42 communicating with the maintaining reservoir 75 remains closed, as are also ports 46 and 47, so that the feed valve operates to maintain the train pipe pressure in the same manner as when in lap position, since the main supply ports 52 and 39 remain open 80 in all of these positions of the valve. The feed valve also furnishes the supply of air to the application chamber in the straight air position of the brake valve, since this drawing off of air from the brake valve 85 chamber acts precisely the same as a leak from the train brake pipe, the pressure in which is maintained by the feed valve at whatever degree was sealed up in the maintaining reservoir. In the straight air lap 90 position, also, the train pipe is in communication with the equalizing reservoir through ports 43 and 44 and cavity 56, so that these pressures remain equalized. It will therefore be seen that the engine brakes 95 may be released and applied or controlled as desired, independently of the train brakes, and while the latter are applied without in any manner affecting the train brakes. If all brakes are released at the 100 time it is desired to apply and release or control the engine brakes independently, this may be done by turning the brake valve to its straight air positions in precisely the same manner as before described, since at 105 this time the train pipe with the equalizing reservoir and the maintaining reservoir are substantially recharged to the normal degree, consequently this degree of pressure will be sealed up in the maintaining reservoir 110 when the brake valve is moved to its straight air positions and the feed valve will operate to maintain this train pipe pressure constant, as before described. It will now be evident that not only may the engine 115 brakes and train brakes be controlled independently of each other, but that when engine brakes are being operated at the time that the train brakes are off, the train pipe pressure is maintained against leakage, 120 so that the air pressure throughout the train pipe and auxiliary reservoirs of the train will not become depleted, no matter how long the brake valve remains in the straight air positions; and also, that when the engine 125 brakes are being operated independently at the time that the train brakes are applied, the train pipe pressure will not be increased by a further supply of air which would cause an undesired release of the 130

train brakes, but the train pipe pressure is then merely maintained constant at whatever degree previously obtained, so that the train brakes are not affected. By this means, the same positions of the brake valve may be used for controlling the engine brakes independently of the train brakes, either when the train brakes are released or when they are applied, which is a great

10 advantage.

In the emergency position of the brake valve, as shown in Fig. 14, the large train pipe port 39 is open to the atmosphere through port 54, cavity 51 and ports 53 and 15 40, while the equalizing reservoir is vented through ports 62 and 41, and the maintaining reservoir through ports 42 and 63, thereby producing a sudden reduction in train pipe pressure to produce quick-action of the 20 triple valves throughout the train in the usual way.

While I have described the maintaining feature as forming a part of the feed valve device, it will be obvious that it may be separately constructed, if desired, and also that the feed valve instead of being connected by pipes may be connected by cored passages in the casings of the engineer's brake valve and feed valve, and may be located otherwise 30 than shown in the drawings.

Having now described my invention, what I claim as new and desire to secure by Letters Patent is:—

1. An engine brake equipment, comprising 35 a main reservoir, train brake pipe, and mechanism operating in response to variations in train pipe pressure to apply the engine brakes, and an engineer's brake valve having positions with ports for controlling 40 the supply of air to and its release from the train pipe to operate the engine brakes and the automatic train brakes, and another position for releasing the engine brakes, without affecting the train brakes and for supplying air to the train pipe to compensate for leakage.

2. An engine brake equipment, comprising 50 a main reservoir, train brake pipe, and mechanism operating in response to variations in train pipe pressure to apply the engine brakes, and an engineer's brake valve having positions with ports for controlling the supply of air to and its release from the train pipe to operate the engine brakes and 55 the automatic train brakes, and other straight air positions with means for applying and releasing the engine brakes independently of the application and release of train brakes and for supplying air to the 60 train pipe.

3. An engine brake equipment, comprising 65 a main reservoir, train brake pipe, and mechanism operating in response to variations in train pipe pressure to apply the engine brakes, and an engineer's brake valve

having positions with ports for controlling the supply of air to and its release from the train pipe to operate the engine brakes and the automatic train brakes, and another position for releasing the engine brakes independently of the train brakes whether the latter are on or off, and means for maintaining the train pipe pressure against leakage.

4. An engine brake equipment, comprising 70 a main reservoir, train brake pipe, and mechanism operating in response to variations in train pipe pressure to apply the engine brakes, and an engineer's brake valve having positions with ports for controlling the supply of air to and its release from the train pipe to operate the engine brakes and the automatic train brakes, and straight air 75 positions for applying and releasing the engine brakes independently of the train brakes whether the latter are on or off, and means for maintaining the train pipe pressure against leakage.

5. In a fluid pressure brake, the combination 80 with a main reservoir and train pipe, of a distributing valve mechanism comprising an application chamber and a valve governed by the pressure in said chamber for controlling the brake cylinder pressure, and an engineer's brake valve having ports for 85 controlling the supply of air to and its release from the train pipe for operating the automatic train brakes, and another position for releasing air from the application chamber when the train brakes are applied and 90 without raising the train pipe pressure.

6. In a fluid pressure brake, the combination 95 with a main reservoir and train pipe, of a distributing valve mechanism comprising an application chamber and a valve governed by the pressure in said chamber for controlling the brake cylinder pressure, and an engineer's brake valve having ports for 100 controlling the supply of air to and its release from the train pipe for operating the automatic train brakes, and another position for releasing air from the application chamber when the train brakes are applied and 105 without raising the train pipe pressure.

7. In a fluid pressure brake, the combination 110 with a main reservoir, engineer's brake valve, and train pipe, of a feed valve device for regulating the train pipe pressure, and 115 means operating when the engineer's brake valve is in release position to hold the feed valve open and supply excess main reservoir pressure to the train pipe.

8. In a fluid pressure brake, the combination 120 with a main reservoir, engineer's brake valve, and train pipe, of a feed valve device interposed between the main reservoir and engineer's brake valve and having a regulating device, the engineer's brake valve hav- 125

ing means for cutting out said regulating device in release position.

9. In a fluid pressure brake, the combination with a main reservoir, engineer's brake valve, and train pipe, of a feed valve device comprising a main valve, a piston for actuating said valve, and a regulating valve operated by train pipe pressure for controlling the pressure on said actuating piston, the engineer's brake valve having means for cutting off communication from the feed valve piston chamber to the regulating valve in release position.

10. In a fluid pressure brake, the combination with a main reservoir, engineer's brake valve, and train pipe, of a feed valve device comprising a main valve, a piston for actuating said valve, and a regulating valve operated by train pipe pressure for controlling the release of fluid under pressure from the piston chamber, the engineer's brake valve having ports for releasing fluid from said piston chamber in release position.

11. In a fluid pressure brake, the combination with a main reservoir, train pipe, and an engineer's brake valve having automatic positions for controlling the train pipe pressure to operate the train brakes, and straight air positions for controlling the engine brakes independently, of a valve mechanism adapted to maintain the train pipe pressure constant at any given degree of reduction, the brake valve having ports for causing the maintaining valve mechanism to operate in the straight air positions.

12. In a fluid pressure brake, the combination with a main reservoir, train pipe, and an engineer's brake valve having automatic positions for controlling the train pipe pressure to operate the train brakes, and straight air positions for controlling the engine brakes independently, of a feed valve for controlling the supply of air to the train pipe, a regulating valve device and a maintaining valve device for governing said feed valve, the engineer's brake valve having ports for cutting out the regulating valve device and causing the maintaining valve device to govern the feed valve in the straight air positions.

13. In a fluid pressure brake, a distributing valve device comprising a valve for controlling the supply of air to the brake cylinder, an application chamber, a differential piston for actuating said valve and having one head subject to the pressure of the application chamber and the other head subject to the brake cylinder pressure, and means for supplying air to said application chamber.

14. In a fluid pressure brake, a distributing valve device comprising a valve for controlling the supply of air to the brake cylinder, an application chamber, a differential piston for actuating said valve and having the larger head subject to the pressure of the application chamber and the smaller head to the brake cylinder pressure, a brake cylinder release valve operated by said piston, and means for supplying and releasing air to and from said application chamber.

15. In a fluid pressure brake, a distributing valve device comprising an application chamber, valve mechanism operated by the opposing pressures of the application chamber and brake cylinder for controlling the supply and release of air to and from the brake cylinder, a valve having a port for supplying air to said application chamber, a graduating valve for controlling said port, and a piston subject to the train pipe pressure for operating said valve.

16. An engine brake equipment comprising a main reservoir, train pipe, and mechanism operating in response to variations in train pipe pressure to effect an application of the engine brakes, a single handled brake valve having a straight air application position for controlling the engine brakes independently of the train brakes, and a valve mechanism for maintaining the train pipe pressure constant in the straight air application position of the brake valve.

In testimony whereof I have hereunto set my hand.

WALTER V. TURNER.
